United States Patent Office

Des. 210,632
Patented Mar. 26, 1968

210,632

TYPEWRITER

John Svezia, Millburn, N.J., assignor to Olivetti Underwood Corporation, New York, N.Y., a corporation of Delaware

Filed May 25, 1967, Ser. No. 7,260

Term of patent 14 years

(Cl. D64—11)

F/G. 1

Des. 210,632

PAGE 2

FIG. 2

FIG. 3

FIG. 4

FIG. 5

FIGURE 1 is a front perspective view of the typewriter showing my design;

FIGURE 2 is a rear perspective view thereof;

FIGURE 3 is a right-hand side elevation thereof;

FIGURE 4 is a top plan view thereof; and

FIGURE 5 is a front view thereof.

The dominant features of the invention are shown in solid lines in the drawings, conventional keys and other conventional elements being shown in broken lines.

I claim:

The ornamental design for a typewriter, substantially as shown and described.
